DRAFT TUBE FOR HYDRAULIC TURBINES OR OTHER FLUID MOTORS.

Application filed April 14, 1916. Serial No. 91,037.

This invention relates to rotary fluid motors and has for its object to increase the efficiency by discharging the fluid from the runner so as to utilize its velocity head to increase the proportion of the total pressure head effective upon the runner.

The invention is applicable to fluid motors in general, whether using liquid, air, gas, steam, or other vapor, but is especially described herein with reference to hydraulic turbines having runners of great power, and high specific speed. Recent development of the hydraulic turbine has been in the direction of increased sizes of units, with runners of great power and high specific speed. Further progress calls for improvements along the following lines: 1. Increase in specific speed of runners without sacrifice of efficiency, or increase of the maximum efficiency of runners of high specific speed; 2. Increase in part-gate efficiencies of such runners; 3. Increase in the power under overspeed conditions, or when operating at constant speed under heads below normal; 25 4. Reduction in the dimensions of the water passages and the space occupied by the turbine and its setting. In hydraulic turbines constructed according to previous practice, increase of specific speed has been found to 30 reduce part-gate efficiencies, but to provide some advantage in maintenance of power capacity under conditions of varying head. It has been heretofore considered impracticable to devise means for improving one of these 35 factors without injuring the other, but I have discovered a practicable means by which both of these factors are improved, as well as the others above listed.

I have found that one of the chief causes 40 of the low maximum efficiency of high specific speed turbines, or the poor part-gate efficiencies, or the limited power under heads below normal, is the inefficient discharge of water from the runner in an oblique direction instead of perpendicular to the motion of the runner. This oblique discharge, which is called for by theory, and has been verified experimentally, includes a "whirl component" in the discharge from 45 the runner. If the water with such a whirling motion enters a straight draft tube of ordinary design, much of the kinetic energy contained in the whirl is lost; and in draft tubes having a sharp bend near the runner 50 the energy of whirl is not only entirely lost but may even increase the disturbances in the tube, and so tend to obstruct the flow. Under part-gate or overspeed conditions (such as exist under reduced head) the whirl rapidly increases and represents a large loss 55 of energy.

The object of this invention is the conversion of the velocity head comprised in this whirl into a pressure head so as to increase the proportion of the total pressure head which can be utilized by the runner. The means disclosed for accomplishing this broadly consists of a draft tube shaped as a volute or spiral and having an annular discharge passage of uniform entrance width 60 receiving the discharge from the runner and progressively increasing in cross sectional area. This tube is designed to receive the water discharged from the runner in an oblique direction and to conduct it in a spiral 65 passage of continually increasing cross-sectional area, so that from the time the water leaves the runner until it enters the tailrace its velocity is gradually reduced, not only 70 with respect to its axial component, as in the ordinary type of draft tube, but in its total resultant value.

Turbine draft tubes as heretofore usually built are nothing more than ordinary conical or uniform pipes with axes either straight, 75 or curved substantially in one plane in any given portion, and the total quantity of water discharged by the runner flows through every section. The spiral draft tube of this 80 invention, however, passes around the runner discharge space in a circumferential direction, receiving the entering water through an annular opening on the side of the passage, and the quantity of water flowing 85 through each section is not the same, but varies with the angular position of the section. As usually constructed, such a tube will terminate in a portion tangent to the spiral, this 90 terminal portion forming a closed pipe similar to an ordinary draft tube.

The boundary walls of such a spiral draft tube may be formed in a large variety of ways; and the invention is not limited to any particular method of design or construction 95 of spiral. These walls may be generated by a line of any desired form contained in a meridian plane revolving about a fixed axis lying in said plane. This generating line while always remaining in the revolving meridian plane is not to remain fixed relatively 100

105 110

to the meridian plane, but is continually to change its length and shape as the plane revolves, in such a manner that it always terminates in two fixed points in the plane, while continually enclosing more and more area as it advances from its initial position to its successive following instantaneous positions. The two fixed points in the meridian plane which always terminate the line 10 will describe the upper and lower (or outer and inner) circular edges of the annular entrance space of the draft tube. The axis of revolution of the meridian plane will in general coincide with the axis of rotation of the 15 turbine runner. As special cases of this method of development, are included the spiral or volute expanding radially in a plane, and the helicoidal or screw surface developing axially. The generating line may for 20 simplicity of construction be given rectangular or circular forms, and the passage may be bounded by surfaces of revolution combined with helicoids or spiral cylinders, or both.

25 As ordinarily applied, the areas of the passage will increase in passing around the spiral in the same direction as the motion of the turbine runner; but in order to obtain modified characteristics for the turbine, for 30 special cases, the opposite direction of attachment can be used. The spiral draft tube of this invention is applicable to conical turbines or turbines of the inward, outward, parallel or mixed flow, action or reaction 35 types, whether having horizontal or vertical shafts and either one or several runners.

A further object of this invention is to 40 provide a draft tube of relatively small dimensions which will cooperate with a variety of types of turbines to improve their design and reduce the sizes of their settings. The dimensions of the turbine in the direction of the shaft axis are important in horizontal turbines as affecting the overall length 45 of the unit and the length of shaft between bearings, and in vertical units because the depth of excavation and height of power house structure are involved. The spiral form of draft tube may be so designed as to 50 develop but slightly in an axial direction and so permit the overall length of the turbine to be made a minimum. Furthermore, the terminal portion of the draft tube tangent to the spiral is offset from the center line of the 55 turbine. This permits horizontal shaft units to be placed on solid foundations not pierced by the draft tube. Moreover, a deep pit can now be provided if desired beneath the generator without interfering with the tube.

60 In the accompanying drawings disclosing the invention as applied to a hydraulic turbine:

Fig. 1 is a plan view of the draft tube;

Fig. 2 is a diagrammatic representation of the development of the tube;

Fig. 3 is a view of the discharge end of the draft tube;

Fig. 10 is a similar view showing a rectangular cross-section;

Fig. 11 is a diagram showing a double 90 spiral draft tube, one opening oppositely to the other;

Fig. 12 shows an application of this invention to a double horizontal turbine, and

Fig. 13 is a diagram illustrating a development of the invention in which two of the 95 sides are rectilinear.

Figs. 14, 15 and 16 are respectively a plan, sectional elevation and outside elevation showing a development in which the central core is cylindrical, the other surfaces 100 being formed as in Fig. 13.

In Figs. 1 to 5, the invention is illustrated in connection with a hydraulic turbine of the inward and downward flow type in which A is the inlet passage from the penstock, B, the runner on shaft 1, and C the draft tube. The inlet is provided with stationary guides or vanes 2 which direct the water into the guide vane passages between the adjustable guide vanes or wicket gates 105 11, from which the water is discharged against the blades or vanes 3 of the runner B rotating in ring 4 and discharging the water downwardly and obliquely in the direction of movement of the runner. There 111 is thus imparted to the discharge water under usual conditions of operation a whirl component following the direction of the rotation of the runner and having considerable velocity energy. To impose a minimum 117 resistance to this whirl and transform its kinetic energy into pressure head which can be utilized by the turbine, the draft tube C is of a spiral or volute form developing in the direction of the natural whirling path of 122 the discharged water and gradually increasing in cross-section to reduce the velocity of the outflow. As herein shown, as for example in Figures 2-13, the spiral develops 128 axially simultaneously with its radial devel-

60

128

130

opment, although in special cases the development may be principally in a radial plane as above described.

In the embodiment illustrated in Figures 1 to 7, the draft tube is formed as a void in the concrete setting of the turbine. It can equally well be cast or built of plates, or castings. One of the terminals of the generating line in the revolving meridian plane is point 5 which is in a curved line starting at about the plane of the lower edge of the runner and curving downwardly and inwardly toward the other terminal of the generating line at point 6. However, point 5 may be below the runner if desired as shown for instance in Figs. 1^a and 5^a.

Between the point 5 and the inner surface of revolution 15, for example, the boundaries of the draft tube are generated by a line of varying length and contour in the revolving meridian plane terminating at one end in the central surface of revolution 15 and at the other end at a point in the outer surface of revolution 30 of the annular discharge passage receiving the discharge from the runner and forming the diffuser chamber designated 23. The smallest area of the draft tube as seen in vertical section is at the top in Figure 2, and as the meridian plane revolves, the point in the successive cross-sections of the tube corresponding to 6, travels downwardly and outwardly on the central cone of revolution 15. This central surface may also be a cylinder. The diffuser or transition chamber 23, located between the blades and the entrance of the spiral draft tube and contained between the inner surface of revolution 15 and the outer surface of revolution 30 is of generally conical form.

To illustrate graphically the development of the sectional form of the tube in Fig. 1 successive cross-sectional contours of the draft tube are shown in Fig. 2 superposed one upon the other in the same plane, the sectional contours all having in common the line 5, 6, across the annular inlet.

The draft tube is formed by revolving the meridian plane so as to bring these contours in order into successive angular positions, this operation being illustrated diagrammatically in Fig. 8. In Figures 2, 4, and 5, the sectional form of the draft tube is shown at 90° intervals, Figure 4 showing the contours at 90° and 270°, and Figure 5 showing the contours at 0°, 180° and 360°. As shown in Figures 3 and 5, when the draft tube has been developed to 360° and opposite the starting point, it has progressed sufficiently axially and radially to pass clear of the starting point and has a section bounded by surfaces of revolution 30 and 15 and spiral surface 18.

Up to 360° the draft tube has an annular opening at its top to receive the discharge

water, and is thereafter closed-over, as seen in Figures 3 and 5. The closed-over portion of the tube beyond the spiral continues to expand in cross-section to the outlet 24 so that there is a continued transformation of 70 velocity head into pressure head down to the tail water. The amount of radial or axial pitch of the spiral may be varied to meet the requirements of each installation and the pitch in either direction may be 75 made zero. Supporting piers or vanes may be provided extending across the closed-over discharge passage, shaped to conform to the proper path of the fluid, and capable of strengthening the passage, or directing the 80 flow of the fluid therethrough, or both. Such piers or vanes are shown in Figures 14 and 15.

In the draft tube shown in Figs. 1^a and 5^a the beginning of the spiral at 5", 6" is 85 spaced further from the runner than in Figs. 1 to 5. Commencing with a section 4, 30°, 5", 6", 15°, 0, successive angular positions of the rotating meridian plane will give at 180° the section shown at 4, 30°, 18°, 90 15°, 0, and at 90° a form of section intermediate between the two sections above outlined. At 360° the draft tube is closed over as indicated at 5", 18°, 6" and passes under the entrance edge 5", 6" of the spiral. At 95 270° the section cut by a meridian plane is intermediate in shape between section at 180° and the section 4, 30°, 5", 18°, 6", 15°, 0 at 360°. The annular passage 23 receiving the discharge from the turbine runner at 4 extends 100 down between the flaring surfaces of revolution 15° and 30° to the spiral surfaces which collect and turn the flow into the tangential outlet conduit leading to tail water at 24°.

By this invention the discharged water is received and guided in the direction at which it leaves the runner and all components of its velocity are gradually reduced and transformed into pressure head which will counteract the tail water pressure and increase the proportion of the total head utilized by the runner. Thus instead of opposing any component of the velocity of the discharge water and creating disturbances which interfere with the runner, the discharging currents are allowed to flow in their natural directions and a large portion of the kinetic energy of the discharge is changed into pressure head which is utilized by the turbine. 110 115 120

Figures 6 and 7 show the application of the invention to each stage of a multistage inward flow turbine. In these figures, 31 is the inlet, 32 are guide blades, and 33 the first stage runner mounted on vertical shaft 125 34. To receive the water discharged from runner 33, casing 35 is formed in accordance with this invention of spiral or volute form developing radially and axially and increasing in cross-section in the direction of the 130

flow. This outlet or interstage draft tube 35 is developed more than 360° and sufficiently radially and axially to clear itself. At 360° it is closed-over and the radial pitch 5 of the spiral is reduced so that it continues in a nearly circular path to the point 36 where its radial pitch is reversed and its cross-section gradually reduced to form an inlet passage 37 to another stage. The draft 10 tube 38 of this latter stage is similar to draft tube C described above. In this double stage turbine the shaft 34 is common to both runner 33 and runner 40.

In this way the two stages of the turbine 15 are combined and the discharge water from the first stage is carried down and admitted to the second stage without any sudden changes in velocity or direction. The whirl component imparted to the water by the first 20 runner is not lost, but its velocity head is utilized.

It is apparent that the relative amount of axial and radial development may be varied within wide limits and, as in case of an outward flow turbine with horizontal axis, there 25 may be no axial development, the draft tube then taking on the form of a spiral or volute in a single plane perpendicular to the axis of the runner.

30 Figure 8 shows diagrammatically, in oblique projection the development of the draft tube of this invention, the vertical line a, b , being the axis of rotation and the planes $a, b, c, d; a, b, e, f; a, b, g, h; a, b, i, k$, each having the section of the tube therein indicated. The plane a, b, i, k , is the starting plane or its position at zero degrees. In Figure 9 is shown an exterior perspective view of a draft tube according to this invention broken away so as to show the curved interior surface. In Figure 10 the surfaces are rectilinear, the inner surface of the tube being a surface of revolution as in the previous form. In Figure 11 is shown the invention applied to a double draft tube in which, owing to the simultaneous axial and radial development, one tube can lie within the other, both having a common axis. In Figure 12, the invention is shown applied to a horizontal double turbine unit in which the runners are within the casings 40, 41, and mounted on shaft 42, and discharge toward each other into the spiral draft tubes 44, 46 and 45, 47, respectively. These draft tubes 55 are right and left handed and start at different points in the circumferences approximately 180° apart, so that the large section of one will be opposite the small section of the other, and one can nest within the other without consuming excessive horizontal length. By this construction, the space required is reduced, permitting the axial 60 length of the turbine to be made a minimum.

In Figure 13, and more particularly in Fig. 16 the draft tube is shown in successive

contours as being bounded by two surfaces of revolution 15, 30, by a screw surface or helicoid 52 and by a spiral cylinder 53, the corners between all surfaces being preferably filleted in a manner similar to that 70 shown in Figure 10. The tube so formed would be similar to that shown in Figures 1, 2, 3, 4 and 5 with the exception that the contours in Figure 2 would be replaced by those in Figure 13. Figures 14, 15 and 16 75 show respectively the plan, sectional elevation and outside view of a tube similar to that last described with the exception that the center core is modified to take the form of a cylinder. 80

By applying this invention to a twin center discharge turbine, the spiral draft tubes can begin at different points in the circumference and thus bring the large part of one opposite the small part of the other in order 85 to save space. This saving of space is illustrated in Figure 12. Also with multiple spirals, they can start at different parts of the circumference and thereby subdivide the space circumferentially, or can be radially one within another, and developing in the same or the opposite direction as shown in Figure 11. Looking down on the discharge outlet along the turbine axis, the complete 90 discharge passage has a horizontal circular section at 5, 5', but the circular partition 6, 6' divides this into an inner circular portion and an outer annular portion. The outer annular portion is bounded below by the descending helical wall whose upper edge 100 is at 5, 6. The inner circular portion within the points 6, 6' has a co-axial cone with its vertex near 6'', 6''', and around this are the two lower descending spiral walls whose upper edges are respectively 5'' 6'' and 5''' 105 6'''.

By the above invention the kinetic energy of the whirl hitherto lost is utilized as pressure head to extend the range of good performance of turbines with respect to varying head, speed and gate opening. With this invention an actual increase in specific speed is allowable and may be made without loss of efficiency and with an actual gain in part-gate efficiencies and an increase in 110 the power developed under overspeed conditions and when operating at constant speeds under heads below normal. The spiral character of the draft tube of this invention enables it to carry the water away from the runner axis, reducing the dimensions of the draft tube along the axis of the shaft. This permits the installation of a bearing close to the runner on the discharge side, with ample space for access to the bearing, and avoiding the obstruction and losses caused by the turbine shaft passing through the draft elbow. The offset terminal portion of the draft tube can be located in any convenient manner with respect to the runner and 120 125 130

permits the turbine setting to be varied within wide limits, as above pointed out.

5 I do not wish to confine this invention to the particular embodiments herein described, but intend to include such modifications thereof as fall within the scope of the appended claims.

Having thus described my invention, I declare that what I claim as new and desire 10 to secure by Letters Patent, is:—

1. In a hydraulic turbine, the combination of a runner and a discharge casing in position to receive water therefrom, said casing comprising a spiral draft conduit in which 15 there is a greater increase in the stream line across sections at successive positions in the direction of flow than in the stream line cross sections of the portions of the opening for the admission of water thereinto between the beginning of the spiral and the 20 respective first mentioned cross sections.

2. In a hydraulic turbine, the combination of a runner and a discharge casing in position to receive water therefrom, said casing 25 comprising a spiral draft conduit in which the difference between any two successive stream line cross sections is greater than the stream line across section of the portion of the opening for the admission of water 30 thereinto between such first mentioned two cross sections.

3. In a hydraulic turbine, the combination of a runner and a discharge casing in position to receive water therefrom, said casing 35 comprising a spiral draft conduit in which each stream line cross section is greater than the stream line cross section of the portion of the opening for the admission of water thereinto between the beginning of the spiral 40 and such first mentioned cross section.

4. In combination, a turbine runner, a spiral discharge casing around the runner axis to receive the discharge water from the runner, and a tangent conduit to receive the 45 discharge water from said spiral casing, a cross-section across the lines of flow in said casing increasing from point to point along the direction of flow so as everywhere gradually to reduce the velocity of the flow 50 therethrough.

5. In combination, a turbine runner and a discharge casing therefor comprising a spiral conduit and a transition space to conduct the water from the runner to said spiral 55 conduit, said casing having an outer wall spreading outwardly from the runner axis on lines of gradual curvature continuously curving in the same direction and an inner wall spreading outwardly so spaced from said outer wall at all points that the transverse width between said walls measured in a meridian plane varies gradually from point to point in any such meridian plane, and said 60 spiral conduit portion of the casing being formed by a side wall connecting said inner

and outer walls and receding from the turbine axis in the direction of the outflow so that successive meridian sections of said casing will have a gradual variation of area.

6. In combination, a fluid motor having a runner and a draft tube having a passage disposed circumferentially around the discharge space of the runner and so formed that the areas of meridian sections at successive angular positions progressively enlarge at a continually increasing rate as the passage is traversed in a circumferential direction.

7. In combination, a turbine runner, a casing therefor and a velocity reducing spiral conduit around the runner axis for the discharge water from said runner, said casing comprising a transition space to conduct the water from the runner to the said spiral conduit.

8. In combination, a turbine runner, and a discharge casing therefor comprising a spiral-helical discharge conduit from the runner; an outer boundary wall of said conduit having the form of a surface of revolution diverging from the runner and co-axial therewith.

9. A fluid motor having a runner and a spiral-helical discharge conduit therefrom, a substantial part of the wall of said conduit nearest the runner being formed as a surface of revolution.

10. A fluid motor having a runner and a discharge passage therefor bounded in part adjacent to the runner by a surface of revolution of substantial extent with elements oblique to the axis and also bounded in part by a spiral cylinder composed of straight line elements parallel to the runner axis.

11. In combination, a turbine runner and a discharge passage therefor bounded by two surfaces of revolution co-axial with the runner with elements oblique to the runner axis and by a spiral cylinder comprising elements parallel to the runner axis.

12. In combination, a turbine runner, a discharge passage therefor bounded by two surfaces of revolution co-axial with the runner with elements oblique to the runner axis and by a spiral cylinder comprising elements parallel to the runner axis, and a transition conduit to conduct the water from the runner to the said discharge passage.

13. In combination, a turbine runner and a spiral discharge conduit for the water from the runner, each meridian section of said discharge conduit comprising a line at a right angle to the runner axis and an outer boundary line parallel to said axis, said lines receding respectively from and along said axis for successive meridian sections.

14. In combination, a turbine runner and a spiral discharge conduit for the water from the runner, the wall for said conduit comprising a surface of revolution of substan-

tial extent adjacent to the runner with elements oblique to the runner axis, each meridian section of said discharge conduit containing at least one straight line element joined to said surface of revolution.

15. In combination, a turbine runner and a discharge conduit for the water from said runner bounded in part by a helicoidal surface and a spiral cylindrical surface.

10 16. In combination, a turbine runner and a discharge conduit for the water from said runner, said discharge conduit having four boundary walls, namely, an inner surface of revolution, an outer surface of revolution, a

15 helicoid surface joining said inner surface, and a spiral cylindrical surface joining said helicoid surface and said outer boundary surface.

17. In combination, a turbine runner and 20 a discharge conduit for the water from said runner, the boundary surfaces of said dis-

charge conduit comprising an inner surface of revolution, an outer surface of revolution and a spiral helicoid generated by a straight

25 line which continually remains in a meridian plane containing the axis of the turbine, but varies in length and in its position in the plane as the plane revolves about the said axis.

30 18. In combination, a turbine runner, a spiral discharge casing therefor extending throughout its course around the axis an in- creasing distance in the axial direction from the runner, the axial distance from the runner being sufficient at the end of approxi-

35 mately a complete revolution of the spiral to permit it to discharge into a laterally en- closed passage extending tangentially from the spiral, and passing beyond the first por- tion of the spiral in the axial direction.

19. In combination, a turbine runner and 40 a draft tube therefor having its course in form compounded of a spiral and a helix, and bounded by surfaces of revolution and surfaces having straight line elements.

45 20. In combination, a turbine runner and a spiral draft tube therefor, having a central core of which meridian sections contain curved lines concave toward the axis.

50 21. In combination, a turbine runner and a spiral draft tube therefor, bounded on the side away from the runner by a curved conical surface which as it recedes from the runner flares into an approximately plane surface normal to the runner axis.

55 22. In combination, a turbine runner with vertical axis, a spiral discharge casing around the runner axis to receive the dis- charge water from the runner, and vane shaped piers in the discharge casing placed edgewise to the flow lines and supporting the upper wall thereof.

23. The combination with a fluid motor 60 having a plurality of stages, of an intermediate spiral discharge passage receiving

the water discharged from one stage and guiding it to the inlet of the succeeding stage.

24. A multiple stage fluid motor including a plurality of runners, and a discharge passage for each runner, at least one of said discharge passages being in the form of a spiral.

25. In a multiple stage fluid motor, the combination with a plurality of stages, of a spiral passage for delivering fluid from one stage to the next stage, and a spiral draft tube from the final stage.

26. In combination, a turbine runner, and a spiral discharge casing around the runner axis to receive the discharge water from the runner, a cross section across the lines of flow in said casing increasing from point to point along the direction of flow so as every- where gradually to reduce the velocity of the flow therethrough.

27. In combination, a turbine runner, a casing therefor, and a velocity reducing spiral conduit around the runner axis for the discharge water from said runner.

28. The method of increasing the effective- ness of a hydraulic turbine which consists in permitting stream elements of the water leaving the runner to continue in their nat- ural discharge directions along a plurality of similar spiral paths in a stream symmet- rical about the turbine axis and continuous around its circumference, then guiding said stream elements in a unitary spiral stream extending through a limited portion of the circumference, and everywhere continuously expanding such spiral stream elements in cross-section, whereby all components of ve- locity of the discharge water are utilized to continuously convert their velocity head into pressure head to increase the net effective head on the turbine.

29. The method of increasing the effective- ness of a hydraulic turbine which consists in discharging the water from the runner vanes in its natural whirling direction and thence guiding it in a path comprising a uni- tary spiral course followed by a tangential course, and at all stages of said path gradu- ally spreading the stream elements to in- crease the cross section of said spiral stream and correspondingly decreasing their veloc- ity, whereby the energy of the whirl compo- nent of the velocity of the water is utilized to counteract the tail water pressure and to increase the net effective operating head.

30. The method of increasing the effective- ness of a hydraulic turbine which consists in discharging the water from the runner vanes in its natural whirling direction and thence guiding it in a path comprising a uni- tary spiral course followed by a tangential course, and gradually spreading the stream elements to increase the cross section of the spiral stream and correspondingly decreas-

ing the velocity of said spiral stream, whereby the energy of the whirl component of the velocity of the water is utilized to counteract the tail water pressure and to increase the net effective operating head.

31. The method of increasing the effectiveness of a hydraulic turbine which consists in discharging water from the runner vanes in its natural direction in a plurality of spiral paths within a space contained between two surfaces of revolution, and then guiding it in a unitary spiral stream of continuously increasing cross-section and correspondingly decreasing velocity whereby its kinetic energy is converted to increase the net effective pressure head on the turbine.

32. A discharge casing for a turbine runner comprising inner and outer walls flaring outwardly from the turbine axis and a side wall connecting said inner and outer walls and receding from said axis in the direction of flow of the discharge so as to form a passage guiding and decelerating the discharge along spiral lines and continuously converting its velocity energy into pressure head to reduce the back pressure on the turbine runner.

33. In a hydraulic turbine, the combination with a runner, of a discharge casing in position to receive water therefrom, said casing comprising a spiral draft conduit in which the differences in area between successive cross sections spaced at equal angular intervals about the runner axis continuously increase in the direction of flow.

34. In combination, a turbine runner and a discharge casing therefor comprising a spiral conduit and a transition space to conduct the water from the runner to said spiral conduit, said casing having its elements everywhere smoothly curved and free from abrupt changes of direction whereby it guides both the whirling components and the meridian components of flow in lines which are everywhere smoothly curved and free from abrupt changes of direction, the sectional areas of said casing measured normally to either component of the motion varying gradually and without sudden changes and meridian sections thereof being free from points of inflection except at their outermost parts.

35. In combination, a turbine runner and a discharge passage therefor bounded in part by a surface of revolution having a generating line so curved that successive elements of this line continuously increase their angle of inclination with respect to the runner axis as they recede from the runner so as to approach more and more nearly to perpendicularity to the axis, and adjoining said surface of revolution a spiral cylinder composed of straight line elements parallel to the runner axis.

36. In combination, a turbine runner and

a spiral draft tube therefor, bounded in part by two surfaces of revolution co-axial with the runner, each generated by lines convex toward a point on the runner axis distant from the runner on the discharge side thereof.

37. In combination, a turbine runner and a discharge passage therefor, bounded by two surfaces of revolution co-axial with the runner, each generated by a line convex toward a point on the runner axis distant from the runner on the discharge side thereof, and by a spiral cylinder comprising elements parallel to the runner axis.

38. In combination, a turbine runner and a spiral draft tube therefor bounded in part by a surface of revolution co-axial with the runner, generated by a line convex toward a point on the runner axis distant from the runner on the discharge side thereof.

39. In combination, an axial discharge turbine rotor, and a spiral draft tube formed to decelerate the flow of the fluid discharged from said rotor.

40. In combination, an axial discharge turbine rotor, and means for simultaneously guiding the fluid discharged from said rotor in a common spiral course and decelerating the flow of said fluid.

41. In combination, an axial discharge turbine rotor, means for outwardly directing the axial discharge flow, and means associated with said direction-changing means for guiding the fluid in a common spiral course and decelerating the flow.

42. In combination, an axial discharge turbine rotor, means for outwardly directing the axial discharge flow and for partially decelerating said flow, and means forming a spiral collecting chamber associated with said direction-changing means for further decelerating said flow.

43. In combination, an axial discharge turbine rotor, means for outwardly directing the axial discharge flow and for partially decelerating said flow, and means forming a spiral collecting chamber surrounding said decelerating direction-changing means for further decelerating said flow.

44. In combination, an axial discharge turbine rotor, guide vanes extending longitudinally of the turbine axis for controlling the inlet to said turbine, means for outwardly directing the axial discharge flow and for partially decelerating said flow, and means forming a spiral collecting chamber communicating with said direction-changing means for further decelerating said flow.

45. In combination, a turbine having an inwardly directed inlet and an axially directed discharge, means for axially directing the inward inlet flow, means for outwardly directing the axial discharge flow and for initially decelerating said flow, and means forming a spiral collecting chamber

communicating with said discharge flow direction-changing means for finally decelerating said flow.

46. In a multiple stage fluid motor, the combination with a plurality of stages, of a passage between said stages comprising an inter-stage draft tube of annular form adapted to regain both whirling and meridional components of flow, and delivering 10 the fluid from one stage to the next stage.

47. In combination, a draft tube for a turbine and a single body within and surrounded by said tube, the said body having a curved sectional profile and an unobstructive outer surface, the diameter of said body 15 gradually increasing in the outlet direction, and the inner part of the tube surrounding said body being gradually enlarged in the said direction.

48. In combination, a draft tube for a turbine, a turbine runner, and a single body within and surrounded by said tube and leading directly from the runner, the said body having a curved sectional profile and 20 an unobstructing outer surface, the diameter of said body gradually increasing in the outlet direction, and the inner part of the tube surrounding said body being gradually enlarged in the said direction.

49. In combination, a draft tube for a turbine; a rotatable turbine runner; and a single non-rotatable body within and surrounded by the tube, the surface of the runner leading directly into that of the body, 35 said last-named surface being unobstructing and said body having a curved sectional profile and of a diameter which gradually increases in the outlet direction, and the inner part of the tube surrounding said body 40 being gradually enlarged in the same direction.

50. A draft tube for a turbine and a single body projecting into the tube from a wall thereof and surrounded by part of the tube, 45 the said body having an outer surface, the diameter of which gradually increases in the outlet direction, and the inner part of the part of the tube surrounding said body being gradually enlarged in the said direction.

51. A draft tube for a turbine and a single body within the tube and connected with a wall thereof and surrounded by part of the tube, the said body having an outer surface, 55 the diameter of which gradually increases in the outlet direction, and the inner part of the part of the tube surrounding said body being gradually enlarged in the said direction.

52. The combination with a fluid motor having a runner with an axial discharge, of a draft tube therefor comprising inner and outer flared surfaces of revolution gradually curving away from the axial direction adjacent the runner to form between them a

flaring annular passage extending from the runner and adapted to receive a whirling discharge and guide it and decelerate it on expanding spiral lines so as to decelerate both the rotational and meridional components 70 of velocity and convert them into effective pressure head.

53. The combination with a fluid motor having a runner with an axial discharge, of a draft tube therefor comprising an outer 75 surface of revolution convex toward the runner axis and curved to gradually turn the outer flow lines outward from an axial direction adjacent the runner toward a radial direction, and an inner core having a surface of revolution spaced from said outer surface so as to provide an annular passage 80 extending from the runner and adapted to guide a whirling discharge on expanding spiral lines to continuously and gradually 85 reduce the velocity of flow and convert velocity head into pressure head while the flow is being turned outward.

54. The combination with a fluid motor having an axial discharge, of a draft tube 90 therefor comprising a central core extending into proximity with said motor and having an inner conical surface of revolution concave toward the axis of the runner to gradually turn the inner flow lines outward to 95 toward a radial direction, and an outer portion having a surface of revolution spaced from the inner surface of revolution so as to provide an annular passage adapted to guide a whirling discharge on expanding spiral lines to continuously and gradually 100 reduce the velocity of flow and convert velocity head into pressure head while the flow is being turned outward.

55. An annular discharge passage for a 105 fluid motor having uniform entrance width and comprising an outer portion with a surface of revolution convex toward the runner axis and flaring outward from adjacent the runner, and an inner core having a conical surface of revolution with its apex at 110 the runner axis and adapted to gradually turn the inner flow lines outward toward a radial direction, said inner and outer surfaces being formed and spaced with relation 115 to each other so that the annular passage is adapted to guide a whirling discharge on expanding spiral lines to continuously and gradually reduce the velocity of flow and convert velocity head into pressure head 120 while the flow is being turned outward.

56. An annular discharge passage for a fluid motor having uniform entrance width and comprising an outer portion with a surface of revolution convex toward the runner axis, and an inner core having a conical surface of revolution beginning close to the discharge end of the runner and adapted to gradually turn the inner flow lines outward toward a radial direction, said inner and 125 130

outer surfaces being formed and spaced with relation to each other so that the annular passage is adapted to guide a whirling discharge on expanding spiral lines to continuously and gradually reduce the velocity of flow and convert velocity head into pressure head while the flow is being turned outward.

57. The combination with a turbine runner, of a draft tube passage therefor comprising an outer surface of revolution beginning close to the discharge end of the runner and curved to gradually turn the outer flow lines outward toward a radial direction and an inner surface of revolution beginning close to the discharge end of said runner and curving to gradually turn the inner flow lines outward toward a radial direction, said inner and outer surfaces being spaced with relation to each other so as to provide an annular passage adapted to guide a whirling discharge on expanding spiral lines to continuously and gradually reduce the velocity of flow and convert velocity head into pressure head while the flow is being turned outward.

58. The combination with a turbine runner of inlet means therefor having guiding means adapted to impart a variable whirl to the inflow, and a draft tube passage for the discharge from said runner comprising an outer surface of revolution convex toward the runner axis and curved to gradually turn the outer flow lines outward toward a radial direction, and an inner surface of revolution spaced from said outer surface so as to provide an annular passage adapted to guide a whirling discharge on expanding spiral lines to continuously and gradually reduce the velocity of flow and convert velocity head into pressure head while the flow is being turned outward, said surfaces of revolution being spaced with relation to each other to give a rate of deceleration of the flow greater than that of a straight conical tube the sides of which taper at 15° with respect to the axis.

59. The combination with a turbine runner of inlet means therefor having guiding means adapted to impart a variable whirl to the inflow, and a draft tube passage for the discharge from said runner comprising an inner conical surface of revolution concave toward the axis of the runner to gradually turn the inner flow lines outward toward a radial direction, and an outer surface of revolution spaced from the inner surface of revolution so as to provide an annular passage adapted to guide a whirling discharge on expanding spiral lines to continuously and gradually reduce the velocity of flow and convert velocity head into pressure head while the flow is being turned outward, said surfaces of revolution being spaced with relation to each other to give a rate of

deceleration of the flow greater than that of a straight conical tube the sides of which taper at 15° with respect to the axis.

60. In combination, a turbine runner with vertical axis, a masonry foundation structure below the runner having an outflow conduit formed therein and a series of metal stay vanes in said conduit standing around said vertical axis and supporting the upper wall of said conduit on the lower wall thereof, each such stay vane having small thickness transverse to the direction of flow and being set at a suitable angle to a plane through the vane containing the turbine axis, so as to offer small resistance to the outflowing water.

61. In combination, a turbine runner with vertical axis, a masonry foundation structure below the runner having an outflow conduit formed therein and a series of metal stay vanes in said conduit standing around said vertical axis and supporting the upper wall of said conduit on the lower wall thereof, said stay vanes being shaped in conformity with spiral paths of flow of the water.

62. In combination, a turbine runner with vertical axis, a masonry foundation structure below the runner having an outflow conduit formed therein and a series of metal stay vanes in said conduit standing around said vertical axis and supporting the upper wall of said conduit on the lower wall thereof, said vanes shaped in conformity with expanding spiral paths of flow of the water.

63. In combination, a turbine runner with vertical axis, a masonry foundation structure below the runner having an outflow conduit formed therein and a series of metal stay vanes in said conduit standing around said vertical axis and supporting the upper wall of said conduit on the lower wall thereof, said stay vanes being similarly inclined to radii thereto from said axis.

64. In combination, a turbine runner with vertical axis, a masonry foundation structure below the runner having an outflow conduit formed therein and a series of metal stay vanes in said conduit standing around said vertical axis and supporting the upper wall of said conduit on the lower wall thereof, each said stay vane being oblique to radii thereto from said axis so that said stay vanes stand edgewise to discharge water flowing with a whirl component from the turbine.

65. In combination, a turbine runner with vertical axis, a masonry foundation structure below the runner having an outflow conduit formed therein, said conduit spreading downwardly and outwardly around said axis on every side, and a series of metal stay vanes in said conduit standing around said vertical axis and supporting the upper wall of said conduit on the lower wall thereof, each such stay vane hav-

ing small thickness transverse to the direction of flow and being set at a suitable angle to a plane through the vane containing the turbine axis, so as to offer small resistance to the outflowing water.

66. In combination, a turbine runner with vertical axis, a masonry foundation structure below the runner having a spiral outflow conduit formed therein and a series of metal stay vanes in said conduit standing around said vertical axis and supporting the upper wall of said conduit on the lower wall thereof, each such stay vane shaped in conformity with spiral paths of flow of the water.

67. In combination, a turbine runner with vertical axis, a masonry foundation structure below the runner having a spiral outflow conduit formed therein and bounded on its lower and inner side by an upward conical projection of the lower wall of said conduit coaxial with the runner, and a series of metal stay vanes in said conduit standing around said vertical axis and supporting the upper wall of said conduit on the lower wall thereof.

68. In combination, a turbine runner with vertical axis, a masonry foundation structure below the runner having an outflow conduit formed therein, the lower wall of said conduit projecting upward conically toward the runner and coaxial therewith, and a series of metal stay vanes in said conduit standing around said vertical axis and supporting the upper wall of said conduit on the lower wall thereof.

69. In a hydraulic turbine the combination with a runner discharging the flow axially and with a forward tangential component at all gate openings so that the absolute velocity of the discharging water always has a component in the direction of rotation of the runner, of a spiral draft tube receiving the discharge from said runner and decelerating it to convert its velocity energy into effective pressure head.

70. In a hydraulic turbine the combination with a runner discharging the flow axially and with a forward tangential component at all gate openings so that the absolute velocity of the discharging water always has a component in the direction of rotation of the runner, of a spiral draft tube receiving the discharge from said runner and decelerating it to convert its velocity energy into effective pressure head, the initial point of the spiral being situated on that side of the turbine toward the final outlet of the draft tube.

71. In a hydraulic turbine the combination with a runner discharging the flow axially and with a forward tangential component at all gate openings so that the absolute velocity of the discharging water always has a component in the direction of ro-

tation of the runner, of a central conical core spreading the discharge water outward in all directions and a spiral draft tube receiving the discharge from said runner and decelerating it to convert its velocity energy into effective pressure head.

72. In a hydraulic turbine the combination with a vertical shaft turbine runner discharging the flow in a generally axial direction, of a shaft conduit comprising a downwardly directed initial passage receiving the flow from the runner and decelerating it to convert velocity head into pressure head, and a substantially horizontal terminal passage receiving the flow from said initial passage and laterally offset with respect to the center line of said turbine.

73. In a hydraulic turbine the combination with a vertical shaft turbine runner discharging the flow in a generally axial direction, of a draft conduit formed in a concrete sub-structure and comprising a downwardly directed initial passage receiving the flow from the runner and continuously decelerating it to convert velocity head into pressure head, and a substantially horizontal terminal passage receiving the flow from said initial passage and laterally offset with respect to the center line of said turbine, said terminal passage continuing the deceleration of the flow to further convert the velocity head into effective pressure head.

74. In a hydraulic turbine the combination with a turbine runner adapted to discharge the flow as a whirling axially progressing stream, of a draft tube receiving said flow and formed with cooperating surfaces extending in a generally axial direction near the runner and turning toward an outward direction away from the axis and spaced to gradually and continuously decelerate the whirling velocity components of said flow, while simultaneously turning the meridian components of said flow from axial toward a direction outwardly from the axis.

75. A draft tube for a hydraulic turbine adapted to receive from the runner of said turbine a whirling axially progressing flow and gradually and continuously to decelerate both the meridian and whirling velocity components of said flow while turning said flow from axial to a direction outward away from the axis, and an enlarging discharge passage receiving said outward flow and having a general direction substantially normal to the runner axis but horizontally offset with respect to said runner axis so as to receive a portion of said flow tangentially.

76. The combination with a hydraulic turbine of a draft tube therefrom comprising a central conical core beginning closely adjacent to the discharge edge of the runner, and side surfaces extending from said runner and cooperating with said core, said core and side surfaces forming between

them an annular passage gradually increasing in cross section in the direction of flow so as to convert the velocity head of the discharge into effective pressure head at the outlet of said annular passage.

77. The combination with a hydraulic turbine of a draft tube therefrom comprising a central conical core having its surface concave and beginning closely adjacent to the discharge edge of the runner, and correspondingly convex side surfaces extending from said runner, and cooperating with said core, said core and side surfaces forming between them an annular passage gradually increasing in cross section in the direction of flow so as to turn the flow from axial toward a direction outward away from the axis and simultaneously to convert the velocity head of the discharge into effective pressure head at the outlet of said annular passage.

78. In a hydraulic turbine the combination with a vertical shaft turbine runner adapted to discharge the flow substantially axially, of a draft tube receiving said flow and formed with cooperating surfaces extending in a generally axial direction near the runner and turning outward away from the axis and spaced to gradually and continuously decelerate said flow while simultaneously turning the flow from axial to an outward direction away from the axis within a relatively short axial distance below said runner, so as to reduce the overall depth of the turbine, the vertical height of said draft tube being less than three times the diameter of said runner.

79. A draft tube for a hydraulic turbine comprising a passage with its surfaces formed to give a gradual and continuous increase in cross sectional area of the flow while simultaneously turning the flow from an axial direction at entrance toward an outward direction away from the axis at discharge and with a spiral surface beginning in the axial flow portion of the tube and extending to the outward flow portion of the tube.

80. A draft tube for a hydraulic turbine comprising a passage with its surfaces formed to give a gradual increase in cross sectional area of the flow while turning the flow from an axial direction at entrance toward an outward direction away from the axis at discharge and with a surface formed as a spiral with an entrance edge extending transversely across the flow in the generally axial portion of said tube so as to divide said flow.

81. A draft tube for a hydraulic turbine comprising a passage with its surfaces formed to give a gradual increase in cross sectional area of the flow while turning the flow from an axial direction at entrance toward an outward direction away from the axis at discharge and with a surface formed as a spiral

with an entrance edge extending transversely across the flow in the generally axial portion of said tube so as to divide said flow and with its discharge portion extending in a generally outward direction away from the axis to form a surface of the discharge portion of said draft tube.

82. A draft tube for a hydraulic turbine comprising a passage with its surfaces formed to give a gradual increase in cross sectional area of the flow while turning the flow from an axial direction at entrance toward an outward direction away from the axis at discharge and with one of its surfaces formed as a spiral with an entrance edge extending in a radial plane transversely across the flow in the generally axial portion of the tube so as to divide said flow and with its discharge portion extending in a generally outward direction away from the axis to form a surface of the discharge portion of said draft tube, said spiral surface gradually and continuously twisting from the radial plane of its entrance edge to the generally outward direction of its discharge portion.

83. A draft tube for a vertical shaft hydraulic turbine comprising a passage with its surfaces formed to give a gradual increase in cross sectional area of the flow while turning the flow from vertical direction at entrance toward a horizontal direction at discharge and with a surface formed as a spiral with an entrance edge extending transversely across the flow in the generally vertical portion of the tube so as to divide said flow and with its discharge portion extending in a generally horizontal direction to form a surface of the discharge portion of said draft tube, said spiral surface gradually and continuously twisting from the direction of its entrance edge to a generally vertical position in the discharge portion of the draft tube.

84. In a hydraulic turbine, a discharge passage formed to receive the water vertically at entrance and to turn it and discharge it horizontally, and a dividing wall or partition therein, having an entrance edge near the inlet end of said tube extending approximately horizontally along a radius of the tube, and said partition having a surface generated by the rotation of a line about the axis while said generating line moves downwardly so as to form a generally helicoidal surface for said partition in the entrance portion thereof.

85. In a hydraulic turbine, a discharge passage formed to receive the water vertically at entrance and to turn it and discharge it horizontally, and a dividing wall or partition therein, having an entrance edge near the inlet end of said tube extending approximately horizontally along a radius of the tube, and said partition in its in-

let portion having a generally helicoidal form so that, at entrance, it is inclined to a meridian plane to conform to the tangential components of the flow discharge by the 5 runner.

86. In a hydraulic turbine a draft tube adapted to convert velocity head into pressure head and comprising walls formed to receive the flow axially and turn it toward 10 an outward direction away from the axis and with a partition in the draft tube extending transversely across the flow lines and dividing the flow.

87. In a hydraulic turbine a draft tube 15 adapted to convert velocity head into pressure head and comprising walls formed to receive the flow axially and turn it toward an outward direction away from the axis and with a partition in the draft tube having 20 its entrance edge extending transversely across the flow lines to divide the flow and with its surfaces forming guiding surfaces for the flow and curved around to extend 25 as surfaces of the discharge portion of the draft tube.

88. In a hydraulic turbine having a vertical shaft runner, a draft tube adapted to

convert velocity head into pressure head and comprising walls formed to receive the flow vertically and turn it toward a horizontal 30 direction and with a partition in the draft tube having its entrance edge extending transversely across the tube to divide the vertical flow and having a surface curving around to guide the flow and to form a generally vertical surface in the discharge portion of the draft tube.

89. A draft tube which when applied to a vertical shaft turbine comprises surfaces formed to receive the water vertically at 40 entrance and to turn it and discharge it horizontally, said surfaces including a portion curving from a side surface of the entrance portion to turn the flow and form a deflecting floor surface in the horizontally 45 directed portion of the tube, and a pier member extending from said floor across the draft tube passage and having its inner entrance portion curved out of a plane surface to conform to a direction of flow at an 50° angle to the final discharge direction.

In testimony whereof I affix my signature.

LEWIS FERRY MOODY.

let portion having a generally helicoidal form so that, at entrance, it is inclined to a meridian plane to conform to the tangential components of the flow discharge by the 5 runner.

86. In a hydraulic turbine a draft tube adapted to convert velocity head into pressure head and comprising walls formed to receive the flow axially and turn it toward 10 an outward direction away from the axis and with a partition in the draft tube extending transversely across the flow lines and dividing the flow.

87. In a hydraulic turbine a draft tube 15 adapted to convert velocity head into pressure head and comprising walls formed to receive the flow axially and turn it toward an outward direction away from the axis and with a partition in the draft tube having 20 its entrance edge extending transversely across the flow lines to divide the flow and with its surfaces forming guiding surfaces for the flow and curved around to extend as surfaces of the discharge portion of the 25 draft tube.

88. In a hydraulic turbine having a vertical shaft runner, a draft tube adapted to

convert velocity head into pressure head and comprising walls formed to receive the flow vertically and turn it toward a horizontal 30 direction and with a partition in the draft tube having its entrance edge extending transversely across the tube to divide the vertical flow and having a surface curving around to guide the flow and to form a generally vertical surface in the discharge portion of the draft tube. 35

89. A draft tube which when applied to a vertical shaft turbine comprises surfaces 40 formed to receive the water vertically at entrance and to turn it and discharge it horizontally, said surfaces including a portion curving from a side surface of the entrance portion to turn the flow and form a deflecting floor surface in the horizontally 45 directed portion of the tube, and a pier member extending from said floor across the draft tube passage and having its inner entrance portion curved out of a plane surface to conform to a direction of flow at an 50 angle to the final discharge direction.

In testimony whereof I affix my signature.

LEWIS FERRY MOODY.

Certificate of Correction.

It is hereby certified that in Letters Patent No. 1,604,361, granted October 26, 1926, upon the application of Lewis Ferry Moody, of Troy, New York, for an improvement in "Draft Tubes for Hydraulic Turbines or Other Fluid Motors," an error appears in the printed specification requiring correction as follows: Page 10, line 75, claim 72, for the word "shaft" read *draft*; and that the said Letters Patent should be read with this correction therein that the same may conform to the record of the case in the Patent Office.

Signed and sealed this 30th day of November, A. D. 1926.

[SEAL.]

M. J. MOORE,
Acting Commissioner of Patents.
